UNITED STATES PATENT OFFICE.

ALBERT T. MARSHALL, OF PETALUMA, CALIFORNIA.

SOUND-REPRODUCING AND PICTURE-EXHIBITING APPARATUS.

Application filed February 9, 1926. Serial No. 87,146.

This invention relates to sound reproducing and picture exhibiting apparatus, and has for its primary object the provision of means whereby the microphone of a radio circuit is preferably employed for the purpose of permitting sound to be distributed simultaneously with the act of projecting pictures of objects or scenes upon an exhibiting screen, where the said pictures of said objects or scenes will visually characterize or depict animated action of the sound produced.

A very important object of my invention pertains to a novel combination of instrumentalities whereby the amplifying horn of the microphone will serve both as a sound distributor and picture exhibitor without depreciating the sound-distributing qualities thereof.

Another object of the invention is to provide apparatus of this character which will be portable and of a design which fits it admirably for the purpose of either home or public entertainment or for advertising purposes, for show windows or public places.

Another object of the invention is to provide apparatus of this character which is simple and highly ornamental.

A still further object of the invention is to provide apparatus having means whereby a film strip, picture slide or the like, can be quickly associated with the sound distributing apparatus as the occasion necessitates.

With the above and other objects in view which will appear as the nature of the invention is better understood, the same consists in the improved construction and novel arrangements of parts which will hereinafter be fully described and particularly pointed out in the claim.

In the accompanying drawings has been illustrated a single and preferred form of the invention, it being, however, understood that no limitations are necessarily made to the precise structural details therein exhibited, but that changes, alterations and modifications within the scope of the claim may be resorted to when desired.

Figure 1 is a front elevation of the apparatus;

Figure 2 is a view in side elevation with parts broken away and parts in section; and

Figure 3 is a view in rear elevation showing the position of parts previous to an operating correlation thereof when projecting

sound simultaneous with the projection of pictures.

In order that those skilled in the art may be sufficiently acquainted with the mechanical details of construction necessary to practice the invention, I will refer generally to some parts that are not wholly essential and in detail to other of the parts which are essential, and in this respect I do not wish to be limited to the precise showing illustrated in the accompanying drawings, so long as these may not be a departure from the scope of the hereto annexed claim.

Therefore, A may represent a suitable ornamental cabinet or enclosure, and same is preferably provided with a front wall B and a rear swinging door C, the latter mounted on hinges D so that the door can occupy either of the positions shown in Figures 2 and 3. The front wall of the cabinet is provided with an opening E, which in this instance is rectangular.

Mounted in the cabinet is conventionally illustrated at 5 such form of microphone as is common with the use of radio receiving instruments. This microphone is connected by a sound conveying tube 6 to the small end of a sound amplifying horn 7. The walls of the horn are relatively flared so that the large end of the horn coincides with the opening E and registers therewith, while the small end of the horn terminates in spaced relation to the aforementioned swinging door C. This small end is covered by a panel 8 of clear glass. It will be observed that the upper end of the sound distributing tube 6 opens into the bottom side of the amplifying horn 7 so that it will not obstruct an imaginary line of vision drawn longitudinally through the horn centrally of the panel 8. It will also be observed that the panel 8, by closing the small end of the sound amplifying horn, compels a projection of the sound toward the large end of the horn.

Within the horn, in suitable spaced relation to the walls thereof and at a point preferably near the front or large end of same, is a picture exhibiting screen 9 which may be formed of ground glass or other suitable well-known material that will enable pictures cast upon one side of the screen to be visible to the eye at the other side thereof. As stated, the screen is in spaced relation to the adjacent walls of the horn 7, and in the space between the marginal edge of the said screen

and said adjacent walls of the horn is a sheet or strip of gauze 9^a, so that the projection of sound from the large end of the horn will not in any manner be interfered with when the 5 microphone 5 is pulsating or functioning.

As previously stated, it is an object of my invention to combine apparatus of the aforementioned type with means that will permit pictures of objects in motion, picture slides 10 containing suitable scenes or the like, to be cast upon the screen where they will be visible to the eye of an observer in front of the horn while the sound is audibly distributed. Only for the sake of showing one way of carrying 15 the invention into practice do I emphasize means for carrying this object in use, and it is in this particular connection that I do not wish to be limited, as any suitable well-known means may be provided for this purpose. 20 However, C, the door of the cabinet A, is used as a support for a picture projecting apparatus which I conventionally illustrate at 10. This apparatus may be of any usual well-known type that will intermittently or pro- 25 gressively draw a film strip 11 across the gate 12 in the operative presence of a projecting lens 13. It will be observed that this lens ex- tends downward and in confronting relation to an inclined mirror 14. It will be further 30 observed that the mirror is in longitudinal alinement with the clear glass panel 8 of the sound amplifying horn 7.

The picture strip 11 may be of the type employing sprocket openings 15 so that the 35 frames of the strip will intermittently register with the gate 12 of the projecting apparatus 10. This film strip may be of the endless variety illustrated herein, and in such event same is mounted to pass over guide pul- 40 leys 16 on the inner face of the door C. These pulleys can be removable from their spindles 17, or otherwise suitably formed in some well-known manner so that the film strip 11, at the 45 option of the operator, can be removed and another one substituted therefor. In lieu of the strip 11 I may use a mechanism for operating slides in the presence of the lens of the projector.

When the door C is closed, as illustrated in 50 Figure 2, the mirror 14 is directly behind the clear glass panel 8. When sound passes from the tube 6 to the amplifying horn 7, it is free to leave the opening E of the cabinet by virtue of the gauze strip 9^a interposed between the 55 screen 9 and the walls of the horn. Assuming that the microphone 5 is in action for the distribution of sound to the amplifying horn, it shall be imagined that the projecting apparatus 10 is functioning for the projection of 60 pictures into the mirror 14, and that due to

the angularity and position of said mirror with respect to said clear glass 8, reflections are cast through said clear glass where they are finally projected onto the exhibiting screen 9. 65

I have stated that pictures of objects in motion or scenes of suitable kind are intended to be projected in synchronism with the action of delivering sound from the apparatus. By this I do not mean that I have shown herein 70 any order of the parts wherein the sound means is automatically timed to function with the picture projecting means. I do mean for the purpose of illustration that the strip 15 can bear any suitable pictures in series or sequence which, when projected upon the screen 9, will characterize animated action of suitable sound. For instance, it can be assumed that the sound coming from the microphone 5 is the reproduction of the voice of a vocal 80 artist, orator or the like, and to make the action of the apparatus entirely animated, the scenes or pictures of the objects on the strip 15 may be images of the person whose voice is being projected through timely actions of the 85 microphone 5.

The projector 10 may be of the electrically actuated type, and in such event a controlling switch 16 can be mounted at the front of the cabinet. The microphone 5, which is also 90 electrically actuated, may be controlled by a similar switch 17.

The feature of the invention upon which I desire to lay particular emphasis is the combination with an amplifying horn of the general 95 character shown and illustrated herein of means for permitting pictures of objects to be projected through the horn where they may be visualized from a point in front of the horn and by means particularly contained within 100 the horn.

I claim:

A sound reproducing and picture exhibiting apparatus comprising a cabinet, a loud speaker mounted in said cabinet and being 105 conical-shaped, a transparent closure for the small end of the loud speaker, a screen disposed in the loud speaker and being spaced a slight distance away from the front, the marginal edges of said screen lying inside of the 110 walls of the speaker for permitting sound waves to pass, a picture-projecting mechanism disposed in back of the speaker for projecting pictures through the transparent closure and onto the screen, a sound producing 115 member, and an open-throated outwardly-flaring tube connecting the last named member with the loud speaker.

ALBERT T. MARSHALL.
